STEREO TAPE RECORDER

Eugene J. Freeman, Studio City, Calif., assignor to Freeman Electronics Corporation, Los Angeles, Calif., a corporation of California

Filed June 3, 1963, Ser. No. 75,187

Term of patent 14 years

(Cl. D26—14)

FIG. 1 is a front elevational view of a stereo tape recorder, showing my new design.

FIG. 2 is a side elevational view thereof viewed from the right hand side of FIG. 1, the left hand side being similar.

FIG. 3 is a bottom plan view thereof.

The top and back, not shown, are plain and unornamented. A portion of FIG. 1 is diagonally lined to indicate transparency. The grille in FIG. 2 is conventional and continuous within the rectangular area.

I claim:

The ornamental design for a stereo tape recorder, as shown and described.
